UNITED STATES PATENT OFFICE.

MARIAN BORDEN HALLIDAY, OF NEW YORK, N. Y.

SIGNALING DEVICE.

Application filed April 6, 1927. Serial No. 181,311.

The present invention relates to an improvement in signal devices. One object has been to provide a manually operated whistle which may be attached to or supported upon the hand of the user in such a way that it can conveniently be operated by the pressure of one or more fingers. It has been noted that traffic policemen and others whose duties require the use of a whistle suffer considerable inconvenience particularly during cold weather when metallic portions of the whistle adhere to the skin of the lips. It has also been found that excessive use of the mouth operated whistle under some climatic conditions is conducive to lung disorders. These and other difficulties arising out of the use of the well known type of whistle will be obviated by the use of a manually operated whistle such as is contemplated in accordance with the present invention.

An embodiment of my invention is illustrated in the drawings accompanying the present specification in which

Figure 1 is an end view partly in transverse longitudinal section.

Figure 2, a central longitudinal section thereof.

Figure 3, a transverse section on the line 3-3 of Figure 1, and

Figure 4, a front view of a modified form.

Referring to the drawings, an air chamber

1 is fitted with a plunger 2 having a hollow

stem 3 which accommodates suitable whistle mechanism part of which is illustrated by the ball 4 lying adjacent to an opening 5.

A finger piece 6 is mounted at the free end of the stem 3 and is positioned to be pressed upon by the fingers of the operator. The plunger 2 is maintained in normal extended position by means of a spring 7.

The device as described is maintained in position on the hand of the user by means of a strap 8 secured in any suitable manner to the chamber 1.

The signal device as described is maintained in position on the hand of the user in the manner illustrated in Figure 1, that is with the strap encircling the user's wrist and with the finger piece 6 in position to be engaged by the user's fingers. When the

plunger 2 is depressed against resistance of

the spring 7 by pressure of the finger, air inside the container 1 is forced through a passage-way 9 in the stem and a passage-way 10 in the plunger into operative contact with the whistle portion of the device. It is obvious that there may be variations as to the type of whistle provided and as to the location and operation of the plunger and spring associated therewith without departing from the main inventive concept.

In the modification illustrated in Figure 4, a container 11 is provided with plunger and whistle mechanism similar to that shown in Figures 1 to 3 inclusive. In addition thereto, a projecting member 12 secured to the container 11 is adapted to engage between the thumb and palm of the hand of the user to maintain the device in operative position during use. Furthermore, a ring shaped finger receiver 13 is secured to the free end of the plunger stem 14 and serves both as a means for maintaining the device in operative position and for depressing the plunger during operation. It will also be apparent that the ring 13 may be used for conveniently attaching the device to a holder or retainer when not in use. Other uses and advantages of the signal device in whatever form it may take will be apparent from a consideration of the foregoing description and the drawings therein referred to.

I claim—

A manually operable signal device comprising an air chamber, a plunger mounted therein and provided with a stem, a whistle in said stem communicating through said stem and plunger with the interior of the air chamber, a lug projecting from a wall of said chamber and adapted to engage a portion of the hand of a user, and a finger piece at the outer end of said stem, said lug and said finger piece being so positioned and related that endwise movement of the air chamber is prevented by the lug when the user presses down against the finger piece in operating the device.

In testimony whereof, I have signed my name to this specification this 1st day of April, 1927.

MARIAN BORDEN HALLIDAY.
